UNITED STATES PATENT OFFICE.

SAMUEL I. BERGER, OF NEWARK, NEW JERSEY.

MECHANICAL TOY.

Application filed August 16, 1924. Serial No. 732,517.

My invention relates to that class of mechanical toys wherein a miniature vehicle is apparently drawn by animal figures and in which a motor is provided to give motion 5 to the vehicle and to the figures.

It is an object of my invention to provide new and positively acting means for imparting a galloping motion to the animal figures.

Another object of my invention is to so arrange and mount the parts as to permit a simple and easy assembly, to increase the rigidity of the toy and reduce friction in the movable parts.

A further object in my invention is to locate the brake or catch controlling the motor in such manner as to prevent sticking and insure its release when the toy is set on the ground.

Other and further objects of my invention will be apparent from the description below.

For purposes of illustration, I have shown and will now describe an embodiment of my invention, but it is to be understood that my invention is not limited except as specified in the claims.

In the drawing accompanying this specification;

Fig. 1 is a side elevation of the toy.

Fig. 2 is a rear view, partly in cross-section, of the driving shaft.

Fig. 3 is a detail showing the action of the brake.

Fig. 4 is a view, partly in plan, and partly in horizontal section, of the front end of the toy.

Fig. 5 is a perspective view of the cross bar 26.

The case or cart 1, which is designed to simulate a sleigh, encloses and supports all the driving mechanism, consisting of a spring motor and a shaft driven thereby. The spring motor, which may be of any usual type, but which is preferably similar to the one shown in the Patent Number 1393936 granted to me October 18, 1921, comprises shaft 2, winding handle 3, ratchet 4, pawl 5, and spring 6. A squared shaft 40

7, the driving shaft, has one end loosely mounted as at 8 in a wall of the cart 1, while the other end enters a vertical slot 9, in the opposite wall of the cart 1. The shaft 7 has secured thereto a gear 10, which is driven from the motor by means of the train of gears 11. Secured to the shaft 7 are

wheels 12, 13, which extend through the slots 14, 15, in the bottom wall of the case 1. To the outer side of wheel 13 is secured the brake or catch consisting of a stamped channel having side walls substantially triangular in shape. In one position the brake enters the slot 15, the said slot being shaped to cooperate therewith, and abuts against one of the edges of the slot as shown in full lines in Figure 3.

The shaft 7 is furthermore provided with a crank 17, upon which are loosely journaled pitmen 18, 19 which are retained in position by washers 20, 21. Pitman 18, 70

passes through a guide opening in cross bar 22, and carries the figure 23, which is designed to simulate the driver of the sleigh. Cross bar 22 is supported in the walls of the case 1, as shown diagrammatically at 24. Pitman 19 is guided by and extends through openings in the front wall of the cart, and is provided at its forward end with a vertically and upwardly extending portion 25 which passes loosely through a hole 39, provided in the cross bar 26.

Cross bar 26 is provided with depending flanges 37. Each of the flanges 37 has a slot at the middle through which the guide 27 passes, and an attaching tab, 33, at each 80

end. Guide 27 consists of an approximately U-shaped wire or rod having the open end of the U secured to the front wall of the cart 1. The closed end of the U is bent upwardly in a curve as at 28 for a purpose 90 presently to be mentioned.

The cross bar 26 carries, at opposite ends, the figures 29 representing the draft animals. Each of these figures is composed of two stamped halves 30, 31, joined edge to edge as is usual in the art. The inner half 31 is provided with an opening, 32, through which extends the cross bar 26. The outer half 30 is secured to the cross bar by means of the tab 33. The two halves 100 30 and 31 are then secured together as by means of the tabs 34. For supporting the front end of the toy a roller 35 is provided which is attached to the front end of guide 27 by means of rod 36.

In operation when the toy is held off the ground or is on its side the catch 16 enters the slot 15 and by engagement with the side wall of the latter holds the shaft 7 from rotation; thus preventing the operation of the device and keeping wound the spring of the motor. When the toy is set upright

upon the ground, the wheel 13 is raised automatically, thus releasing the catch and permitting the motor to drive shaft 7. By placing the catch 16 near the wheel 13 at 5 the end of the shaft 7, it can be seen that a small motion will suffice to disengage the catch, thus substantially reducing friction and making the action of the toy more certain. As the shaft 7 revolves the pitman 10 18 transmits an up-and-down motion to the figure 23, while the pitman 19 moves the cross bar 26 and attached figures 29 to 15 and fro along the guide 27. As the cross bar enters on the curved portion 28 an oscillatory motion of the figures 29 about a horizontal axis is produced, which in combination with the reciprocatory motion simulates a galloping motion. It may be noted that the oscillatory motion is dependent primarily upon the curvature and shape of the 20 guide portion 28 and may be proportioned as desired without altering the dimensions of the toy.

I claim;

- 25 1. In a toy, a case, driving mechanism enclosed within the case, a guide supported upon the front wall of the case on the outside thereof, a bar slidably mounted upon the guide, figures carried by the bar, means actuated by the mechanism within the case for reciprocating the bar along the guide, and means, forming a portion of the guide, to impart an additional oscillatory motion to the bar.
- 30 2. In a toy, a bar carrying figures, a guide upon which the bar is slidably mounted, positive means for moving the bar along the guide, and means whereby the guide imparts to the bar a motion of oscillation about an axis parallel to the axis of the said bar.
- 35 3. In a toy, a guide, a bar supported at its middle by the guide and extending freely transversely thereof, figures mounted on the ends of the bar, positive means for reciprocating the bar along the guide, and means forming part of the guide for imparting an oscillatory motion to the bar during its reciprocation.
- 40 4. In a toy, a body member adapted to act as a support for the various parts of the toy, a driving shaft mounted in the body member, a rod actuated thereby, a guide mounted at one end upon the body member and extending freely from the said end, said guide having a curved portion, a cross bar slidably mounted upon the guide and having contact therewith on two lines, and connection between the cross bar and the rod, whereby the cross bar is reciprocated along the guide.
- 45 5. In a toy, a body member adapted to act as a support for the various parts of the toy, a driving shaft mounted in the body member, a rod actuated by the shaft, a cross head connected to the rod and reciprocated

thereby, a guide supporting the cross-head and comprising a pair of tracks extending parallel to each other and curved out of the plane of parallelism, and means for supporting the guide from the body member.

70

6. In a toy, a pair of figures, each figure comprising an inner and an outer part, joined edge to edge, each inner part having an opening, a bar having depending flanges extending at opposite ends through the said openings, and means for attaching each outer part to the respective end of the bar comprising slits in the said outer part and members formed on the said flanges and adapted to extend through the said slits 75 and be bent over.

75

7. In a toy, a guide, a bar engaged with the guide, and adapted to reciprocate along the said guide, figures, one at each end of the bar, each figure comprising an inner and an outer part joined edge to edge, the inner part having an opening engaged with the bar, and means for securing each outer part to the respective end of the bar.

80

8. In a toy, a figure, formed of two parts joined edge to edge, one of said parts having an opening, a support extending through the said opening, and means for attaching the other of the said parts to the end of the support, said means comprising slits in the said other part and tabs formed on the support and adapted to extend through the slits and be bent over.

90

9. In a toy, having movable parts, a case having top, bottom and side walls, a motor supported within the case, a shaft driven by the motor, means for supporting one end of the shaft in a side wall, a wheel mounted upon the shaft, within the case, and adjacent the said side wall and adapted to extend 100 through a slot in the bottom wall, means for loosely receiving the other end of the shaft in another side wall, a wheel mounted upon the shaft, within the case and adjacent the said other side wall and adapted to extend 105 through a slot in the bottom wall; a crank formed intermediate the ends of the shaft, connections from the said crank to a movable part, and a brake mounted on the said shaft at the second mentioned end between 110 the second mentioned wheel and its adjacent side wall and to cooperate with a wall of the case to render the motor inoperative.

100

10. In a wheel toy, a case having bottom and side walls, a shaft, wheels carried by the shaft within the case and near the ends of the said shaft and extending through slots in the bottom wall, means in one of the side walls for supporting one end of the shaft, means in an opposite side wall for loosely receiving the other end of the shaft, a motor for driving the shaft, a brake mounted on the shaft adjacent the second mentioned end thereof between the wheel mounted thereto and the adjacent side wall 130

125

and cooperating with a slot in the bottom wall of the case.

11. In a wheel toy, a case having bottom and side walls, a motor supported within the case, a shaft driven by the motor, means in one of the side walls for supporting one end of the shaft, means in an opposite side wall for loosely receiving the other end of the shaft, wheels mounted at the ends of the shaft adjacent the ends thereof and extending through slots in the bottom wall, and a catch mounted on the shaft between the wheel mounted at the second mentioned end and the adjacent side wall and in position to cooperate with the slot receiving the said wheel.

12. In a wheel toy, a case having bottom and side walls, a motor supported within the case, a shaft driven by the motor, means in one of the side walls for supporting one end of the shaft, a wheel mounted upon the shaft within the case adjacent its said end, and extending through a slot in the bottom wall, means in an opposite side wall for loosely receiving the other end of the shaft, a wheel mounted on the shaft within the case, adjacent the second mentioned end and extending through a slot in the bottom wall, and a catch carried by the second mentioned wheel on the side adjacent the aforementioned opposite side wall and adapted to engage, at times, the slot entered by the second mentioned wheel.

13. In a mechanical toy, a case comprising top, front and side walls, a guide supported at one end upon the front wall of the case and extending exteriorly from the case, a

figure mounted to move along the guide, said guide being formed to produce a combined reciprocating and oscillatory motion of the figure, another figure mounted upon the top wall of the case, a motor within the case, a shaft mounted in side walls of the case and driven by the motor and having a crank formed thereon, pitmen journaled upon the crank and connected to the several figures to actuate the same, wheels mounted upon the shaft within the case and extending through slots in the bottom walls.

14. In a toy, a case having top, bottom and side walls, a motor mounted within the case, a shaft driven by the motor and having one end mounted in a side wall of the case and another end loosely received in an opposite side wall of the case, wheels mounted upon the shaft at the respective ends thereof and within the case and extending through slots in the bottom wall, a brake mounted on the shaft adjacent the loosely received end and adapted to cooperate with a wall of the case to at times render the motor inoperative, a guide supported at one end upon the top wall of the case and extending freely therefrom, said guide being formed with a curved portion, a cross-bar supported and adapted to slide upon the guide, figures carried by the cross bar at its ends, and a connection from the shaft to operate the cross bar.

Signed at Newark in the county of Essex and State of New Jersey this 13th day of August A. D. 1924.

SAMUEL I. BERGER.
